COMBINED CANDLE AND FLOWER HOLDER

Margaret E. Shipley, Pittsburgh, Pa.

Application September 16, 1950, Serial No. 12,230

Term of patent 14 years

(Cl. D48—2)

To all whom it may concern:

Be it known that I, Margaret E. Shipley, a citizen of the United States, residing at Pittsburgh, State of Pennsylvania, have invented a new, original, and ornamental Design for Combined Candle and Flower Holder, of which the following is a specification, reference being had to the accompanying drawings, forming a part hereof.

Figure 1 is a side elevation view of a combined candle and flower holder, showing my new design; and

I claim:

The ornamental design for a combined candle and flower holder, as shown.

MARGARET E. SHIPLEY.
